ABSTRACT: An envelope of head or back cushion receiving the upper end of a U-shaped tubular member which closely fits the envelope and tends to hold it in position, and a two-part button having an element piercing the envelope, said button having a reflective element at least at one side of the envelope and holding the latter against removal from the tubular member.

PATENTED APR 13 1971

FIG. 1

FIG. 2

FIG. 3

INVENTOR

Martin J. Bird

BY *Chas. P. Day*

ATTORNEY

HEAD OR BACKREST AND SAFETY DEVICE FOR CYCLES

BACKGROUND OF THE INVENTION

Cycles of the present day are often provided with safety bars or the like which extend upwardly as for instance from the rear portion of the cycle saddle to a point above the head of the cyclist or at least into the area of the back or neck for the purpose of minimizing injury in case of accident and also in some cases providing for the support of the saddle as from the hub or rear end plates of the rear wheel of the cycle. These safety bars in some cases may be uncomfortable.

SUMMARY OF THE INVENTION

This invention provides for a comfortable padding in the form of an envelope having an open end which is slipped over the U-shaped upper end of a safety bar for a cycle. These safety bars are generally elongated in nature and are usually attached to the hub or rear end plates of the rear wheel of a cycle, extending upwardly to a point where the saddle may be attached thereto and rising above the saddle to a terminal point at the head or the nape of the neck or back of the cyclist. The envelope in the present case is slipped over the upper U-shaped end of the safety bar and is normally held merely by friction, so that it can be removed or stolen with ease. The present invention provides a conventional button comprising a male and a female part, the male part including a roughened spike member which pierces both sides of the envelope and is very firmly connected to the female part which is located at the opposite side of the envelope, providing a locking means to prevent removal of the cushioned envelope and at the same time providing for a e.g. round reflective button at either or both sides of the envelope, but preferably facing the rear.

BRIEF DESCRIPTION OF THE DRAWINGS

FIG. 1 is a front view of the new safety envelope;
 FIG. 2 is a rear view thereof, parts broken away and in section, and
 FIG. 3 is a section on line 3-3 of FIG. 2.

PREFERRED EMBODIMENT OF THE INVENTION

The reference numeral 10 indicates a bent tubular bar which as is well known in the art may be attached at its lower ends, not shown, to the cycle saddle or to the hub or the rear end plates of the rear wheel of the cycle. These bars rise upwardly to a point above or adjacent to the head of the cyclist or in some cases terminate somewhat lower adjacent the nape of the neck or at the back of the cyclist, for the purpose of providing a certain degree of safety in the event of upset of the cycle. Such safety devices are well known and it is believed

need not be further described except that at the upper end thereof it is in the form of an inverted U which is indicated at 12 in FIGS. 2 and 3.

A cushion device in the form of an envelope is provided to slip over the upper end of the safety bar. The envelope is elongated and has two sides 14 and 16, 14 being the rear and 16 the forward side, the latter being embossed as indicated at 18 and providing a more comfortable rear support for the head or back of the cyclist. The envelope has a closed end 20 and an open end at 22 and is slipped over the upper end of the safety bar with a rather light friction fit so that although it stays in position, is easily accidentally removed or stolen.

In the present case there is provided a button comprising two parts generally indicated at 24 and 26. The part 24 in the

15 present case is provided with a roughened spike at 28 which is received in a clutchlike member, not shown but well understood in the art, in the opposite button part 26, thus securing the two plies or sides 14 and 16 of the envelope together at a point below the closed end 12 of the U of the 20 safety bar and between the sides thereof, thus preventing unauthorized removal of the envelope per se.

At least the rearward portion 24 of the button is provided with a reflectorized surface for additional safety reasons and if desired of course the forward portion of the button 26 may 25 also be provided with a reflective surface. The two parts of the button 24 and 26 although relatively thick do not extend beyond the edges of the envelope as at 30, 32, see FIG. 3, as defined and extended by the tubular member 10 located therein.

30 It will be seen that the envelope is easily slipped over the closed end 12 of the U-shaped safety bar and the button parts 24, 26 are then merely positioned and snapped together. This button is of a well known kind which is very difficult to separate once the parts are secured and therefore the 35 cushioned envelope is not easily stolen and cannot be accidentally lost.

I claim:

1. A safety bar for a cycle generally in inverted U-shape having a closed end extending upwardly, an envelope applied thereto, said envelope having a closed end and an open end and being slidable over the closed end of the U-shaped safety bar for light frictional securement thereto, and a fastener comprising two parts, one at each side of the envelope within the area of the closed end of the U-shaped safety bar, means 40 securing the two parts of the fastener together in substantially permanent relationship, said means extending through the envelope and thereby securing the envelope substantially permanently with respect to the safety bar.

2. The safety bar of claim 1 wherein at least one of the parts 50 of the fastener has a reflective surface thereon.
